Attorney

UNITED STATES PATENT OFFICE.

HENRY A. FUNK, OF ST. LOUIS, MISSOURI.

MEANS FOR PREVENTING WEAR IN THE CROTCH OF TROUSERS.

Application filed October 12, 1923. Serial No. 668,054.

To all whom it may concern:

Be it known that I, HENRY A. FUNK, a citizen of the United States, residing at the city of St. Louis, in the State of Missouri, have invented certain new and useful Improvements in Means for Preventing Wear in the Crotch of Trouser, of which the following is a specification.

This invention relates to means for retarding or minimizing wear in garments, and pertains more particularly to means for shielding or protecting the crotch of trousers from undue wear.

In trousers, a variety of causes contribute to the wearing away of the goods at the crotch. In consequence of the alternate back and forth motion of the wearer's legs in walking, the portions of the legs thereof contiguous to the crotch are subjected to a good deal of wear because of the resulting friction. Such wear usually begins from the inside of the trousers, because of the rubbing of the underwear against the inside of the crotch of the trousers. The wear is especially liable to occur in the region pressing against the testicles.

One of the objects of this invention is to retard such mechanical wear of the crotch.

Another object is to prevent the rotting and discoloration of the material of the trousers in that particular location by the perspiration, sweat, or other matters that may be exuded from the body.

Other objects and advantages will be apparent as the description proceeds.

In the accompanying drawings forming part of this specification, in which like numbers of reference denote like parts wherever they occur,

Figure 1 is a side elevation of a pair of trousers to which my invention has been applied, the near leg being shown lifted to expose the crotch;

Figure 2 is a fragmentary plan view of the same on a larger scale, looking at the inside of the trousers when the legs are spread apart;

Figure 3 is a view of a rear leg-section of a pair of trousers, as it appears when cut from the cloth preparatory to forming the complete pair of trousers, and embodying this invention; and

Figure 4 is a section on the line 4—4 of Figure 2.

A substantially triangular-shaped shield 1 of fabric or cloth, having a rubber facing

2 on one side, is secured by means of stitches of thread 3 to the inside of the trousers with the rubber-faced side of the shield against the inside of the underside section 4 of the trousers, or that portion thereof cut to make up the rear of a trousers leg 5. The underside section 4 is shown developed as cut in Figure 3. The curved edge 6 of the shield 1 is sewed to the curved seat seam 7 of the underside section 4, and the short straight edge 8 of the shield is sewed to the inseam 9 of the said section. The thread 3 is preferably, but not necessarily, the same thread which is customarily used along the cut edges of the component sections to prevent the unraveling of the cloth at the said edges. In a pair of trousers, as is well known, there are two such rear leg-sections 4, one being cut right hand, and the other left hand, and both sections are preferably provided with shields 1, which are cut right and left hand respectively, according to which hand rear leg-section 4 they are to be applied.

When the sections 4 have been prepared and have attached thereto the shields 1, and when all the other sections, comprising a pair of trousers have been completed, such component parts are sewn together in the conventional manner, at their seams, to form a complete whole as best shown in Figures 1, 2, and 4. The seams 12 are formed by folding over together the common edges of the section 4 and their intimately contiguous shields 1, as best shown in Figure 4. The thread 13 passes through the shield 1 and the sections of cloth at the seams 12, thus securing the parts together.

It has been determined by experiment that the coefficient of friction between a rubber surface and a fabric or cloth surface is very much less than that between the contacting surfaces of two contiguous fabrics. It can, therefore, be readily understood that in placing the rubber facing of the shield 1 against the inside of the cloth of the crotch 14 of the trousers 11, any tendency towards wearing away of the cloth in that region will be materially lessened, since any friction between the rubber facing 2 and the inside of the crotch 14, due to the motion of the wearer's legs in walking, will be much less than that which might occur were the underwear of the wearer directly in contact with the cloth of the trousers.

Sheeting of rubber alone, and having no fabric reinforcement or backing, may be

used instead of the sheeting hereinbefore described, having fabric on one side and rubber on the other. However, it is preferable to have that side of the shield, adjacent to the wearer, constructed of fabric, because, in pressing the garment, the heat of the iron can not be transmitted directly to the rubber, but is applied against the fabric, which thus protects the rubber. The sheeting can be made of very thin material, which is desirable, for the crotch is a place where any increase of thickness may prove annoying to the wearer.

It is to be noted that the lines of stitching securing the shields 1 to the crotch are those which are conventionally used to sew the back and inside seams, and no additional stitching, such as might impair the looks of the garment if visible from the outside, is needed. Furthermore, the long diagonal edge of the shield 1 is not fastened to the trousers, but is movable thereto, resulting in greater latitude of movement and comfort to the wearer. However, it is not to be understood that this invention is limited in scope to this precise mode of fastening the shield to the crotch, but any suitable method, by other forms of stitching or other means, may be employed.

Attention is also directed to the fact that the shield is preferably, though not necessarily, made in sections separated by the seams; instead of in a single piece, so that it follows intimately the configuration of the trousers at the seams as well as elsewhere, with increased comfort to the wearer.

For the purpose of facilitating the manufacture of the shields in large quantities, the shield is made of such dimensions as to fit the largest size of trousers, the shield being adapted to the smaller sizes by cutting off a portion of the shield. In this connection, it is to be noted in Figure 3, that the diagonal edge 15 of the shield 1 is not joined directly to the edges 6 and 8, but is connected to the intermediate edges 16 and 17, which are approximately perpendicular to the edge 15, and are connected

to the edges 6 and 8 respectively. Any surplus of material in the shield is taken care of by folding or tucking under the edge 15 or by cutting off material along the edge 15 to bring the same closer to the edges 6 and 8.

The shield, being of rubber, also protects that part of the trousers, which its covers, from rotting and discoloration by the perspiration, sweat or other matters that may be exuded from the body. For this purpose a shield of any impervious material may be used, whether or rubber or other material, and irrespective of any qualities it might or might not possess for minimizing the friction against the crotch of the trousers.

This invention is not restricted in its use to the crotch of trousers, but may be applied to other parts of garments.

Neither is it desired to be understood as being limited to the use of rubber for the purpose of reducing or retarding frictional wear of the garment, but any suitable material having similar friction reducing qualities may be substituted for rubber sheeting.

Having thus described this invention, I hereby reserve the benefit of all changes in form, arrangement, order, or use of parts, as it is evident that many minor changes may be made therein without departing from the spirit of this invention or the scope of the following claims.

I claim:

A shield for protecting the crotch of trousers which consists of two triangular-shaped members disposed one on each side of the crotch on the inside of the trousers and secured along two of its edges to the seams of the crotch, the other edge being left free to permit a slight degree of movement of the member with respect to the cloth of the crotch, said triangular-shaped members being respectively faced with rubber on the side bearing against the cloth of the crotch and having the outside faced with a protective covering of fabric.

In testimony whereof I hereunto affix my signature.

HENRY A. FUNK.
